Primary Examiner — Mary Ann Calabrese*Assistant Examiner* — Mark David Wolfley(74) *Attorney, Agent, or Firm* — Heslin Rothenberg Farley & Mesiti P.C.**CLAIM**

The ornamental design for a bench, as shown and described.

DESCRIPTION

FIG. 1 is a front right perspective view from above of a bench according to the new design;

FIG. 2 is a rear left perspective view from below thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The broken lines in the drawings illustrate portions of the bench and form no part of the claimed design.

The long dash-short dash lines in the drawings represent a boundary of the claimed design and form no part of the claimed design.

The breakaway lines in the figures indicate a symbolic break in the length of the design. The appearance of any portion of the design between the breakaway lines forms no part of the claimed design.
